(57) **CLAIM**

The ornamental design for a water heater controller, as shown and described.

DESCRIPTION

FIG. 1 is a perspective view of a water heater controller; FIG. 2 is a front elevation view of the water heater controller of FIG. 1;

FIG. 3 is a right side view of the water heater controller of FIG. 1;

FIG. 4 is a left side view of the water heater controller of FIG. 1;

FIG. 5 is a top side view of the water heater controller of FIG. 1; and,

FIG. 6 is a bottom side view of the water heater controller of FIG. 1.

In the drawings, the claimed design is defined by the shaded surfaces; broken lines immediately adjacent shaded surfaces represent boundaries of the claim and form no part thereof;

(Continued)

all other broken lines depict unclaimed environmental subject matter and form no part of the claim.
